UNITED STATES PATENT OFFICE.

JOHN WHITEHOUSE MALTBY, OF GATES, NEW YORK, ASSIGNOR TO NELLIE R. MALTBY, OF SAME PLACE.

ROADWAY.

SPECIFICATION forming part of Letters Patent No. 619,592, dated February 14, 1899.

Application filed October 21, 1898. Serial No. 694,170. (No model.)

To all whom it may concern:

Be it known that I, JOHN WHITEHOUSE MALTBY, of Gates, in the county of Monroe and State of New York, have invented a new 5 and useful Improvement in Roadways, of which the following is a full, clear, and exact description.

The object of my invention is to provide a foundation for roadways, sidewalks, cross-walks, or bicycle-paths constructed of asphalt or like material or blocks, which foundation may be readily and economically laid and so constructed that the material provided for the foundation will be effectually held in 15 place and prevented from crumbling, sinking, or disarrangement to any appreciable extent.

The invention consists in the novel construction and combination of the several 20 parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of a portion of a road, illustrating the utilization of the improvement in the construction of said road. Fig. 2 is a transverse section taken practically on the line 2 2 of Fig. 1, and Fig. 3 is a 30 transverse section through one portion of the foundation of the road.

In the construction of the road-bed a number of receivers A are employed, and each receiver 35 usually consists of sides 10 and a bottom 11, the sides being provided with inwardly-extending flanges 12. The sides of the receiver are strengthened by bolts 13 and 14, the said bolts serving to hold the sides of 40 the receiver firmly in position. These bolts are arranged in pairs, the bolts of a pair extending from opposite sides of the receiver passing one another, and the inner ends of the bolts are carried downward and secured 45 to the bottom portion of the receiver in any suitable or approved manner.

The receivers are supported upon beams or sleepers 15, that are located transversely of the road-bed, and these beams or sleepers are 50 preferably constructed of wood. In the construction of a roadway any desired number

of receivers A may be employed, one receiver being usually located at the crown of the road-bed extending longitudinally thereof, the other receivers being at each side of said 55 crown or central receiver, and the upper portions of the receivers employed are shaped to conform to the desired curvature of the road-bed.

Each receiver is preferably located upon a 60 bed-plate B, and said bed-plates consist of metal plates 16, bolted or otherwise secured to the sleepers 15, said bed-plates being provided with upwardly-extending members 17, between which the receivers A are snugly 65 fitted.

In constructing the road-bed metal plates 18 are located between the receivers, fitting snugly thereto, so that the road-bed or roadway may be made in sections, and the sections 70 of the road-bed or roadway are completed by introducing asphalt, concrete, or suitable material into the receivers A and between the receivers, as shown at 19 and 20 in Fig. 1, or a suitable plastic foundation may 75 be laid in said receivers, in which blocks of granite or other material may be introduced, if preferred. I wish it to be understood that the receivers may be of any desired width and that receivers of different widths may be 80 employed in the construction of a road-bed, as shown in Fig. 1.

In Fig. 3 I have illustrated a slight modification in the construction of a receiver, in which the bottom of the receiver consists of 85 a plank 21, of suitable thickness, to which side pieces 22 are secured by screws or the like, said side pieces being provided with inwardly-extending flanges 23.

Having thus described my invention, I 90 claim as new and desire to secure by Letters Patent—

1. In the construction of sidewalks, roadways, bicycle-paths and the like, a receiver for concrete or similar material or blocks, 95 said receiver consisting of a base, sides extending upwardly from the base, flanges extending inwardly from the upper edges of said sides, and brace-bolts attached to the sides, which brace-bolts are arranged in pairs, the 100 pairs of brace-bolts extending one beyond the other, their inner ends being carried down-

ward and secured to the bottom of said receiver, for the purpose specified.

2. In the construction of roadways, bicycle-paths and the like, the combination, with
5 a sleeper and a bed-plate secured to said sleeper, having projections extending upwardly from its upper face at intervals apart, of a receiver consisting of a bottom section fitted between the projections of the said bed-
10 plate, sides extending upwardly from the said bottom, flanges extending inwardly from the upper edges of the said sides, and tie-bolts secured to the sides of the receiver, the tie-bolts being arranged in pairs adapted to pass
15 one another, the inner ends of the tie-bolts being carried downward and connected with the bottom portion of the receiver, as described.

3. In a roadway, the combination of a series

of bed-plates having upwardly-extending members, receivers fitted between said members and each comprising a bottom section with flanges projecting upwardly from the edges thereof, plates extending transversely between the receivers, and paving-blocks 25 held in and between the receivers.

4. In a roadway, the combination of a series of bed-plates having upwardly-extending members, receivers fitted between said members and each comprising a bottom section 30 with flanges projecting upwardly from the edges thereof, and paving-blocks held in and between the receivers.

JOHN WHITEHOUSE MALTBY.
